UNITED STATES PATENT OFFICE.

LEE H. PARKER, OF BOSTON, MASSACHUSETTS, ASSIGNOR TO SPRAY ENGINEERING COMPANY, OF BOSTON, MASSACHUSETTS, A CORPORATION OF MASSACHUSETTS.

APPARATUS FOR SPRAYING IN COOLING PONDS AND THE LIKE.

Original application filed February 5, 1916, Serial No. 76,297. Divided and this application filed June 20, 1917. Serial No. 175,843.

To all whom it may concern:

Be it known that I, LEE H. PARKER, a citizen of the United States, and a resident of Boston, in the county of Suffolk and State of Massachusetts, have invented an Improvement in Apparatus for Spraying in Cooling Ponds and the like, of which the following description, in connection with the accompanying drawings, is a specification, like characters on the drawings representing like parts.

This application is a division of my co-pending application Serial No. 76,297, filed February 5, 1916, now Patent No. 1,233,119, dated July 10, 1917.

This invention relates to systems and apparatus for spraying liquid, preferably water in cooling ponds and the like.

In order that the principle of the invention may be readily understood, I have disclosed certain embodiments thereof in the accompanying drawings, wherein—

Fig. 1 is a partial diagrammatic view in side elevation and vertical section of a mixed discharge spraying system embodying my invention;

Fig. 2 is a vertical section of a cooling pond positioned on the roof of a building and certain connections thereof; and

Fig. 3 is a view in vertical section of a fence surrounding the cooling pond and certain means for admitting air to the pond.

Fig. 4 is a partially diagrammatic view in side elevation and vertical section of a mixed discharge spraying system similar to that of Fig. 1 positioned on the roof of a building and provided with a barrier in a manner similar to that illustrated in Figs. 2 and 3.

The pollution of river water from waste products of manufacturing processes, thereby rendering it unfit for use in condensers, has led to the practice of constructing cooling ponds from which condensing water is drawn and to which the hot water from the condensers is returned, thus using the water repeatedly. The object of my invention is to provide a thoroughly efficient cooling system for various purposes, such, for example, as for use in steam engines and steam turbines, and for circulating water through the jackets of gas or other internal combustion engines. Other uses will, however, be apparent and are within the scope of my in-

vention. While my system is not restricted to the use of any particular type of nozzle, I 55 preferably employ the nozzle shown in the United States patent to Eneas, No. 1,101,264, June 23, 1914, the said nozzle being one whereby a very thorough mixture of the jets of water is effected within the nozzle itself, 60 so that the discharged spray may, particularly under high pressure, be very finely comminuted and issue as a wide spray of substantially homogeneous consistency throughout.

While therefore I am not limited to any particular nozzle that referred to peculiarly cooperates in accomplishing an effective cooling of the water as will hereinafter be more fully set forth.

In my said patent, of which this application is a division, I have represented a cooling pond of generally rectangular form and having surrounding walls of suitable material. My invention pertains in its preferable 75 use to a cooling pond of the general type disclosed in said patent. Preferably such pond has an outlet pipe at one corner screened if desired from the body of the pond. The water from the condenser of the 80 engine or other usual source, which is in a highly heated condition, enters through the main pipe. The arrangement of pipes is preferably that shown in Fig. 1 of my said patent, and is also indicated in Fig. 2 of the 85 present application. That is to say, I preferably employ a main pipe from which lead a plurality of parallel pipes extending throughout substantially the length of the cooling pond in a horizontal direction. 90 From each of said parallel pipes lead upwardly at suitable distances distributing pipes from which lead pipes preferably arranged diagonally to the said parallel distributing pipes. From said diagonally arranged pipes upwardly extend the nozzles which are preferably, though not necessarily, of the said Eneas type. In Fig. 2, as stated, I have shown the arrangement of pipes and nozzles disclosed in Fig. 1 of said patent, but 95 have in Fig. 1 merely diagrammatically indicated certain pipes and nozzles; that is, each nozzle indicated in Fig. 1 represents a group of nozzles such as shown at 38 in Fig. 2. Such illustration in Fig. 1 of this 100 application is diagrammatic merely, and the

preferred and detailed arrangement is that shown in Fig. 2 of this application and in said Fig. 1 of that patent.

In Fig. 1, I have represented one form of my invention, whereby what I term a mixed discharge of the water is effected. In said figure I have diagrammatically indicated the condenser at 1, the circulating pump at 2, it being one capable of handling an excess 10 quantity, the cooling pond at 3, the pipe leading from the cooling pond to the pump at 4, and the pipe leading from the condenser to the cooling pond at 5, the latter pipe being provided with nozzles diagrammatically 15 indicated at 6, but which preferably are arranged in sets as shown in Fig. 1 of my said parent patent. The pump 2 is connected with the condenser 1 by means of a pipe 7. Connecting the pipes 5, 7 is a by-pass 8 provided with a valve 9, and the pipe 5 is provided with a check valve 10. By opening the valve 9, a portion of the cooling water may be made to pass around the condenser and not through the same. The pump 2 has 25 the necessary capacity to handle the total water sprayed. The pump may be of any suitable type, but preferably is a rotary pump. By suitably regulating the by-pass valve 9, any portion of the condenser cooling 30 water may be sprayed, or in other words, any desired portion of the water may be circulated through the by-pass instead of through the condenser. The system represented in Fig. 1 is what I term a mixed discharge system, in that the water sprayed 35 may be partially that passing through the condenser and partially that merely circulated through the pond, the pump and the by-pass. By the system herein shown, I may 40 spray more water than passes through the condenser.

A spray system for cooling ponds is in accordance with my invention so arranged as to reduce the amount of drift, that is, spray 45 passing beyond the limits of the pond, to a minimum and to a negligible factor where possible. In certain cases, however, where the available space for the cooling pond is restricted and it is necessary to place one or 50 more sides of the pond near buildings, as, for example, at a distance less than thirty feet from the buildings, I suitably provide means to protect the buildings from spray drift in case of high winds. Preferably also 55 I provide means at the same time whereby the necessary air for cooling the water may be admitted. For this purpose, I have provided what is known as a louvre fence, and I have indicated a section of the same at 24 60 in Fig. 3. Preferably such fence is composed of posts 25 between which are positioned slats 26 of suitable material arranged at a suitable distance apart and inclined substantially as indicated, so as to prevent the 65 outward passage of spray or draft between

the slats. The spray deposited upon the slats slips back into the confines of the pond or onto the ground surrounding the pond within the louvre fence. In order to provide for the admission of air for effecting 70 the cooling of spray water, I preferably provide the fence about the entire pond with a so-called apron 27 positioned at an inclination and spaced sufficiently from the ground to permit the in-rush of air for cooling purposes. I have herein represented the apron 27 as composed of suitably matched boards themselves secured to inclined beams 28 bolted to the posts 25 at 29 and also bolted at 30 to inclined braces 31, the latter in turn secured to posts 25 at 32. The apron 27 is suitably inclined so that the spray drift falling thereon will drain back into the pond or will not interfere with the in-rush of the cooling air. 85

In Fig. 2, I have represented another form of cooling pond which may be employed with the circulating system of Fig. 1 in accordance with my invention. In cases where the space for ponds is very much restricted, they may be located upon the roof of the building. Such a pond, I have indicated in Fig. 2. In said figure, the roof of the building is indicated at 33, it being composed of suitable waterproof material. The roof preferably slopes to the center or some other portion thereof where it is provided with a suitable sump 34, suitably screened as indicated at 35 and connected with a downward spout 36 leading back to the condenser or other source of hot water. Preferably the pond is surrounded by a louvre fence 37 similar to those already described, and the arrangement of piping and nozzles within the pond is preferably such as is shown in Fig. 1 of my said parent patent and is indicated at 38 in said Fig. 2. The system of piping and connections intermediate the pond, the pump, and the condenser may be 100 and preferably is that shown in Fig. 1 of this application already described. 105

In Fig. 4 I have illustrated a spraying system similar to that of Fig. 1 but positioned upon the roof of a building and provided with a barrier in a similar manner as illustrated in Figs. 2 and 3. Similar parts are designated by the same reference numerals as in Figs. 1 to 3. 115

Having thus described certain illustrative embodiments of my invention, I desire it to be understood that although specific terms are employed, they are used in a generic and descriptive sense and not for purposes of limitation, the scope of the invention being set forth in the following claims. 120

Claims—

1. A cooling pond provided with spraying means, and a barrier at one or more sides of the pond, the barrier being provided with an apron at its lower part permitting the 130

admission therebelow of a stream of cool air.

2. A spraying combination comprising a cooling pond having spray nozzles, a barrier at one or more sides of the pond comprising a fence having horizontally arranged, inclined slats, and an apron at the lower part of said fence but spaced from the base thereof to permit the in-flow of cool air.

3. A spraying combination comprising a cooling pond having spraying nozzles, a barrier at one or more sides of the pond having horizontally arranged, inclined slats, and an inclined apron at the lower portion of said fence to direct an in-coming stream of air to the cooling pond.

4. A spraying combination comprising a cooling pond located upon the roof of a building, said pond having an impervious bottom, a down spout leading therefrom to a source of hot water supply, a barrier provided with an air directing apron and surrounding said pond, spraying nozzles within the confines of the pond, and means for delivering heated water to said nozzles.

5. A cooling pond having a plurality of groups of nozzles, each of which is upwardly directed whereby the water is discharged upwardly to fall to the surface of the pond, a barrier at one or more sides of the pond, and means at the lower portion of said barrier for directing a stream of cooling air through said barrier to the surface of the pond.

6. A spraying combination comprising a pond formed upon the roof of a building, said pond having an impervious bottom, a down spout leading therefrom, a barrier surrounding the pond, a line pipe having a plurality of groups of nozzles communicating therewith and located within the con-

fines of the said barrier, said nozzles being each upwardly directed, and means at the lower portion of said barrier but spaced from the base thereof to permit the inflow of cool air.

7. A spraying combination comprising a cooling pond 3 having spraying nozzles mounted thereover and upwardly directed, a condenser 1, piping 5 leading from the condenser to the spraying nozzles, a circulating pump 2, piping 4, 7 leading from the cooling pond to the condenser, a by-pass 8 leading from the piping 7 to the piping 5, a valve 9 therein and adapted to regulate the relative proportion of the flow through said by-pass, and a barrier 37 surrounding said pond and provided with air directing means 27 to direct an incoming stream of air to the pond.

8. A spraying combination comprising a pond formed upon the roof of a building, said pond having an impervious bottom, a down spout leading from said pond, a barrier surrounding said pond and including a louvre fence with inclined slats, and an inclined apron at the lower portion, and spraying nozzles arranged over the pond and upwardly directed.

9. A spraying combination comprising a pond formed upon the roof of a building, said pond having an impervious bottom, a down spout leading therefrom, a series of spraying nozzles mounted over said pond and having upwardly directed nozzles, and a louvre fence surrounding said pond and provided with horizontally arranged inclined slats and an apron at the lower part of the fence but spaced from the base thereof to permit the inflow of cool air.

In testimony whereof, I have signed my name to this specification.

LEE H. PARKER.
